COMBINED CONTROL KNOB AND ESCUTCHEON PLATE

Phillip S. Morse, New York, N. Y.

Application July 9, 1952, Serial No. 20,522

Term of patent 14 years

(Cl. D70—2)

To all whom it may concern:

Be it known that I, Phillip S. Morse, a citizen of the United States of America and a resident of the city of New York, in the county of Bronx and State of New York, have invented a new, original, and ornamental Design for a Combined Control Knob and Escutcheon Plate, of which the following is a specification, reference being had to the accompanying drawing, forming a part thereof.

Fig. 1 is a front view of a combined control knob and escutcheon plate showing my new design;

Fig. 2 is a plan view thereof;

Fig. 3 is a side view thereof; and

Fig. 4 is a rear view thereof.

The characteristic features of my design reside in those portions shown in full lines.

I claim:

The ornamental design for a combined control knob and escutcheon plate, substantially as shown and described.

PHILLIP S. MORSE.
